LIGHTING FIXTURES

David Burliuk, Huntington, and Edward Rambusch, Harrison, N. Y., assignors to Rambusch Decorating Company, New York, N. Y., a corporation of New York

Application March 7, 1956, Serial No. 570,161

2 Claims. (Cl. 240—78)

The present invention relates to lighting fixtures and is more particularly directed toward direct lighting fixtures wherein a concentrated light beam is directed into the desired azimuthal direction and at selected sloping angles for spotlighting of displays, action, or the like.

In fixtures heretofore available for such purposes structural limitations have been such as to limit the angle the beam could make with the vertical and restrict the area over which the beam could be adjusted. Many such fixtures are unable to attain angles of 45° from the vertical. According to the present invention it is readily possible to secure beam angles all the way up to 60° above the nadir.

According to the present invention the objects are available in relatively simple structures which may be readily installed and serviced from below or from the attic. When the servicing is to be done from the attic the adjustments are readily made because it is possible to first adjust the fixture to a position where a sight line is in the position of the axis of the desired beam and to then, with certainty, readjust the fixture so that the light beam is in the position of the sight line. The operator can thus predetermine the direction of the beam to be produced.

The construction provided is one in which one can readily relamp the fixture from the attic with the assurance that the beam can be directed in the previously determined direction.

According to the present invention, the wide adjustment of the lamp position is possible in an extremely shallow structure so that it is well suited for use where limited space is available for recessing the fixture.

Other and further objects of the invention will become apparent as the description proceeds.

The accompanying drawings show, for purposes of illustrating the present invention one embodiment in which the invention may take form, together with modifications thereof, it being understood that the drawings are illustrative of the invention rather than limiting the same.

In the accompanying drawings:

Figure 1 is a vertical sectional view through the lighting fixture designed to permit a 60° tilt of the beam and showing it mounted in the ceiling, the full lines showing the lamp in its uppermost position with axis vertical for down lighting, the peephole being on a 60° sighting line, the dotted lines showing the lamp displaced to its lowest position for lighting objects 60° from the vertical;

Figure 2 is a plan view at reduced scale, taken in the direction of the arrow 2 of Figure 1, parts being omitted and showing the lamp carrier in the same position as in full lines in Figure 1;

Figure 3 is an elevational view at reduced scale, also taken in the direction of the arrow 2 of Figure 1, but showing the lamp carrier turned through nearly 180° so that the peephole is in the position of the lamp of Figure 2, and vice versa;

2

Figure 4 is a view similar to Figure 3, showing the position of the lamp carrier when the peephole is in the position to sight on an object to be lighted by the 50° tilted beam of Figure 5;

5 Figure 5 is a view similar to Figure 2, indicating the lamp carrier turned through an oblique angle such as to produce a beam 50° from the nadir;

Figure 6 is an inverted section at reduced scale taken on the plane 6—6 of Figure 1, showing the internal marking of the lamp carrier;

10 Figure 7 is a section, at reduced scale, taken on the line 7—7 of Figures 1 and 8, illustrating the captive levers for supporting the movable parts of the fixture from the plaster ring;

15 Figures 8 and 9 are fragmentary, sectional views taken on the lines 8—8 of Figure 7, and 9—9 of Figure 6, respectively;

20 Figures 10 and 11 are diagrammatic vertical and plan views illustrating the adjustments available in the fixture;

25 Figure 12 is a diagram illustrating the sighting of the fixture on an object; and

Figures 13 and 14 are fragmentary views of modified forms of construction suitable for larger lamps.

In Figure 1 a conventional ceiling is illustrated at C. 25 To it is secured a plaster ring 10. This ring has an upwardly facing annular trough 11 to receive supporting levers, to be described, a bottom finishing flange 12 engaging the lower surface of the ceiling, a stop member 12a extending inwardly and a plurality of bendable straps 13 or other suitable supports engaging the upper face of the ceiling.

30 This plaster ring supports a lamp box generally indicated at 15 which can be turned through substantially 360° about a vertical axis X—X. As the lamp box is for the purpose of housing the lamp and supporting the lamp carrier, its shape is not critical.

35 The sides of the lamp box shown in the drawings lie approximately in the frustum of a cone which approximates a cylinder. It has sloping side walls 16 secured to a flat bottom plate 17 by clips 18. The bottom plate fits in the flange 12 of the plaster ring and the lamp box is adapted to be passed up into the plaster ring from below. The plaster ring and box walls are usually made from sheet steel.

40 45 The supports for the lamp box include two captive rockers 19, 19 (Figs. 7 and 8), which have outer ends 20 adapted to overlie the inner upper rim of the plaster ring and inner ends 21 inside the lamp box. These inner ends carry jack screws 22 bearing on the plate 17 so that the rockers may be swung out to the full line position of Fig. 6 or swung back to the dotted line position to permit insertion of the lamp box, or its removal. It is thus possible to support the lamp box for adjustment about the vertical axis. A stop 17a carried by the plate 17 engages stop 12a so as to prevent turning it more than 360°.

45 50 The sloping axis of the lamp box walls is indicated at Z—Z, Figs. 1 and 10. It is here shown at 30° from the vertical axis X—X. A lesser angle, for example 22½°, 55 may be selected where narrower areas are to be covered.

The top of the box walls is cut in a plane at right angles to this sloping axis. Across the top of the box walls is a top plate or cover 23, preferably in the form of an aluminum casting and provided with heat radiating fins 23'. Its outside diameter is shown slightly greater than that of the upper end of the tube 16. It rests on this tube and is guided for angular movement about the axis Z—Z by an outside boss or lug 23a and two inside bosses or lugs 23b, and clips 24a, 24b, 24c carried by the side walls of the tube 16. The clip 24a provides a pointer and carries a clamp screw 25 accessible from the attic. The

clips 24b and 24c are narrower. A notch 26 in the cover plate 23 facilitates assembly and disassembly for lamp renewal. As the fixture may be operated and serviced from below, a clamping screw 27 is provided as shown in Figures 1, 6 and 9. It is opposite the outside boss 23a.

The cover 23 forms a lamp carrier. A lamp socket 28 and a projector lamp 29 are carried by the cover 23 with the lamp axis L—L at an angle 60° to the slope of the cover 23. Here, axis L—L is slightly offset from axis X—X. The lamp shown is a PAR-38-150 watt flood or spot lamp.

When the lamp is in its uppermost position in Figs. 1, 2 and 4, as shown in full lines, the axis L—L is vertical and the light beam has 0° tilt and is projected down through the central hole or aperture 30 in plate 17. This aperture is slightly off center to better allow the tilted beam to escape. The cover or lamp carrier 23 can be turned about the sloping axis Z—Z, Figures 1 and 10, so that the lamp axis traverses a cone and the lamp axis is brought to the position L', L', Figures 1 and 10, whereupon the light beam projected from the lamp below the ceiling will be about 60° above the nadir. Suitable means may be provided to prevent turning the cover 23 through more than 360°. In the construction shown, the screw 25 engages the conduit fitting 31 for this purpose.

Reference is now made to Figures 10 and 11, which diagrammatically show the adjustments possible. Here, the vertical axis about which the entire lamp box turns is indicated at X—X. The axis of the cone through which the lamp axis L—L passes when turned about oblique axis Z—Z is indicated at Z—Z. The lower trace line L'—L' of the lamp axis shows how low the lamp can be adjusted and how high the beam may be directed. After converging to an apex and passing through the aperture in the plate, the central ray of the beam diverges from the vertical and also lies in a cone.

When the lamp is in the vertical axis X—X, the spot of light produced in a horizontal work surface is indicated by the small central circle 30', Fig. 11. If the carrier is turned through 180°, the spot is thus centered about the point where line L'—L' meets the floor. This spot will be elongated, as indicated at 30". If the carrier 23 is turned in a clockwise direction viewed from above, the spot 30' will move over the floor in an elliptical path, as indicated at 40, in a clockwise direction. By shifting the carrier back and forth through 180°, it will traverse one half of the ellipse as it sweeps across the region between nadir and 60° from nadir. For reasons to be set forth, it is preferable to be able to turn it through substantially 360°, as indicated.

When the structure is turned about the vertical axis X—X, the axis Z—Z traverses cones up to 120° apex angle, and the axis L'—L' traverses the shell of a cone up to 60° from the nadir. The spot 30' may be made to traverse circles 41, Fig. 11, marked with the angle of beam slope. By concurrent adjustment of the lamp box about the plaster ring and of the lamp carrier about the lamp box, the spot of light may be placed in any azimuthal direction and at any displaced position from nadir within the range provided.

When the adjustment is for an intermediate beam angle, such as 50° indicated in Figures 4 and 5, and in Figure 11, it is possible to have light strike a spot from either of two adjustments, depending upon whether the peephole is turned to its one 50° position as shown in full lines of Figure 4, or its other position, as indicated in dotted lines. When the cover is turned to 180°, the aim is correspondingly changed.

The fixture may be adjusted to aim the beam or may be relamped either from below or from the attic. Where adjustments are to be made from below, the screw 25 is loosened so as to release plate 23. The plate can be turned from below by reaching through the bottom opening 30, and when the screw 27 is loosened, grasping the handle 32 (Fig. 6) and turning the lamp carrier and lamp.

The lower surface of the carrier plate 23 has a set of angle legends, as indicated in Figure 6, which may be brought opposite a spot on the inner wall of the tube 16 to indicate the angle of slope of the lamp axis and light beam. The lamp tilt is 0° in Figure 6. When the jack screws 22 are loosened, the entire lamp box can be turned about the vertical axis to effect azimuthal adjustment. Tightening the screws 22 and 27 then assures that setting and lamp renewals may be effected without disturbing the settings.

When access to the fixture is to be had only through the attic, all adjustments and lamp renewals must be effected from above. To make it possible to aim the fixture, the lamp carrier 23 is provided with a peephole 33, 180° from the lamp mounting. An observer can look through this sight opening as indicated in Figure 12, and through the opening 30 can see where a lamp in that axis will project the light beam.

The carrier 23 is provided with two sets of angle indicia, one for the "peephole tilt" and one for the "lamp tilt." One way of arranging such indicia is shown in Figs. 2 and 3.

In Figure 2 the full lines show the lamp in the vertical axis with 0° tilt, and light goes directly down through hole 30 in plate 17. The peephole is then at a 60° tilt. The reverse position is indicated in full lines in Fig. 3, where the peephole is over the hole 31 and one sees a spot directly below the fixture.

Should one wish to aim the lamp from above in a sloping direction at an object, the screws 22 are loosened, when plate 23 is off. The plate is then replaced and, by turning the lamp box about the vertical axis and the lamp carrier about its axis, one can look through the peephole and sight onto the object, as indicated at Fig. 12. The lamp carrier might, for example, be brought to a position such as the 50° position of Fig. 4. He would then observe the reading of the "peephole" legend opposite the pointer. The carrier would then be removed to afford access to screws 22, these screws tightened, the cover restored and turned, as shown in Figure 5, to bring the corresponding "lamp tilt" indicia opposite the pointer. The lamp axis now is where the sight line formerly was. By having the indicia in duplicate and the cover adjustable through nearly 360°, the cover can be turned in either direction from the stop and cause the spot of light to traverse the path indicated at 40 in Figure 11.

Where a 200 watt PAR-46 flood or spot lamp is desired, the construction shown in Figure 13 may be used. The same lamp box 16 and cover 23 are employed. The lamp 50 is carried in a spider 51 supported by screws 52 and spacer from the top of the cover 23. The cable fitting is indicated at 53. Here, the jamb screw 25' is indicated at the top of the lamp box and it engages the nut 54 on the locking bolt.

Where the fixture is to accommodate a 300 watt lamp, it is made larger. Figure 13 shows a PAR-56 prong base, 300 watt lamp 60 carried in a housing 61 secured in place in cover 62 by a bolt 63.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. A lighting fixture comprising a fixed horizontal supporting ring, an oblique tubular lamp box having a bottom horizontal closure plate with a central aperture and side walls extending up through the ring, means to secure the lamp box to the ring for turning about a vertical axis, an obliquely disposed top plate secured to the lamp box for rotation about an axis extending obliquely upward from a point near the center of the ring, and a projector type lamp bulb carried by the top plate for move-

ment therewith and having the axis thereof disposed at an angle to the axis of rotation of the upper plate equal to the inclination of said axis of rotation of the upper plate whereby the lamp axis, upon turning of the upper plate, may be shifted through a conical path and between angles to the nadir from zero to twice the angle of slope of the axis of rotation of the upper plate, and the light beam projected through said aperture at various angles of tilt and whereby, upon turning of the lamp box about in the ring, the light beam may be projected in various azimuthal directions.

2. A lighting fixture comprising an annular supporting ring adapted to be secured in an opening in the ceiling, a fixture body including a horizontal, centrally apertured plate fitted to the ring to rotate therein about a vertical axis substantially central of the aperture, and having a tubular, oblique, wall-forming portion terminating in an oblique plane at substantially right angles to the axis of the wall-forming portion with its uppermost portion substantially vertically over the center of the ring, means to secure the fixture body to the ring for

movement through substantially 360° about the ring axis, a cover secured to the upper end of the wall-forming portion and secured thereto for rotation about the oblique axis of the wall-forming portion, a lamp secured to the cover near the periphery thereof inside the body forming portion and with its axis with such an angle to the general plane of the cover plate that when the cover plate is turned about the said oblique axis the lamp axis traverses a cone whose steepest trace is vertical and whose lowest trace is at an angle to the vertical twice the angle of obliquity of the oblique axis.
